Primary Examiner — Jennifer Rivard*Assistant Examiner* — April Rivas(74) *Attorney, Agent, or Firm* — Charles T. J. Weigell, Esq.; Fross Zelnick Lehrman & Zissu, P.C.(57) **CLAIM**

The ornamental design for a transparent box with compartments, as shown and described.

DESCRIPTION

FIG. 1 is a top perspective view of a transparent box with compartments showing my new design;

FIG. 2 is a top perspective view thereof, showing the cover under the transparent box with compartments;

FIG. 3 is a front view of FIG. 1, with the back view being a mirror image thereof;

FIG. 4 is a side view with the opposite side view being a mirror image thereof;

FIG. 5 is a top view thereof; and,

FIG. 6 is a bottom view thereof.

The shadows and reflections shown in the drawings form no part of the claimed design.

1 Claim, 6 Drawing Sheets(56)
